(57) **CLAIM**

The ornamental design for a pleated necktie, as shown and described.

DESCRIPTION

FIG. 1 is a front view of a pleated necktie showing my new design.

FIG. 2 is a rear view of a pleated necktie showing my new design.

FIG. 3 is a front perspective view of a pleated necktie showing my new design.

FIG. 4 is a rear perspective view of a pleated necktie showing my new design.

FIG. 5 is a side view of a pleated necktie showing my new design.

FIG. 6 is an end view of a pleated necktie showing my new design; and,

FIG. 7 is an upper perspective view of a pleated necktie enlarged and fragmented for purposes of illustration.

Any shading and cross-hatching are not features of the design but are utilized to illustrate the surface contours of the pleated necktie in the drawings.
